his Attorney

UNITED STATES PATENT OFFICE.

WARREN COLE, JR., OF KNOXVILLE, TENNESSEE.

AXLE-LUBRICATOR.

SPECIFICATION forming part of Letters Patent No. 392,906, dated November 13, 1888.

Application filed May 17, 1888. Serial No. 274,179. (No model.)

To all whom it may concern:

Be it known that I, WARREN COLE, Jr., a citizen of the United States, residing at Knoxville, in the county of Knox and State of Tennessee, have invented certain new and useful Improvements in Axle-Lubricators; and I do hereby declare the following to be a full, clear, and exact description of the invention, such as will enable others skilled in the art to which it appertains to make and use the same.

My invention relates to that class of axle-lubricators in which a grease-tube passes through the hubs of wheels, in combination with a plug or plunger for forcing the grease down upon the axle while the wheels are on. Heretofore great annoyance has been experienced in losing the plugs from their places by constant jarring and droppings from the wheels; and the object of my invention is to overcome these obstacles by devising means whereby the plunger will always be securely locked in position and the locking mechanism shielded from injury, and a further object being to construct the plunger-handle in such a manner that it will combine strength and durability and can be manipulated with greater facility.

With these ends in view my invention consists in the mechanism more fully described hereinafter, and pointed out in the claims.

Referring to the accompanying drawings, Figure 1 represents a side elevation of my complete device, partly in cross-section; Fig. 2, a rear end view of a hub to which my device is applied, and Fig. 3 a detail view of the tube.

The reference letter *a* indicates an ordinary wagon-hub provided with a metallic box, *b*. The grease-tube *c* passes through the hub at a point between the rear end and the spokes, and its exterior surface is smooth, except the lower part, which is provided with a sufficient number of threads, *d*, to engage with the threaded aperture *e* in box *b*. When the tube is in place, the upper extremity is flush with the outer surface of the hub. An internal rabbet, *f*, is also provided for the reception of the shoulder *g* upon the upper part of the plunger. In order to facilitate the insertion of the tube, a pair of recesses, *h*, are made in its upper edge, which are located diametrically opposite each other to receive a screw-driver or like instrument. The plunger is provided

with a laterally-extending handle, *i*, having a single coil, *j*, which forms a spring for its outer free end, *K*, the coil and free end being located near the front edge of the spoke to facilitate handling from the outside of the wheel. This free end *K* extends up away from the hub in a plane substantially at right angles to the body portion *i*, so that when bent back in locking adjustment it will constantly press the plunger downward and hold it tightly in place. A hook, *l*, is inserted in one of the spokes, upon the inside, a short distance above the hub, and engages the free end of the handle when the same is pressed forward against the resistance of the spring.

As an extra precaution against accidental displacement, and also to more rigidly and securely hold the plunger in place, I provide a lug, *m*, which consists of a piece of flat metal attached by screws *n* to the rear face of the spoke. The upper surface of this lug is beveled off to allow the handle to slide down over it when the plunger is being inserted, and it projects beyond the side of the spoke and at a distance above the hub sufficient to allow the handle to be locked under it. The lower surface of the handle bears upon the top of the hub-band, which serves as a fulcrum when the handle is locked or being locked in position. The handle is so constructed that the spring-coil and free end will lie between the spokes and be shielded by them.

In operating my device grease is first inserted in the lubricant-receptacle *c* and forced down by the plunger. When the plunger has been forced home, it is given a slight turn laterally to bring the handle *i* between the locking-lug and hub-band. The free end *K* of the handle is then sprung forward and put in engagement with the catch upon the spoke, or when the modification shown in dotted lines is used the hooked end *r* is made to engage with the inner edge of the spoke. When thus locked, the plunger will be securely held in place against any possible displacement from the rotation of the wheel or the usual causes. As the handle is made of a round bar of iron, any mud or droppings which may collect upon it can be easily removed by jarring it against a solid substance.

It is evident that my invention could be varied in numerous ways which might suggest

themselves to a skilled mechanic. Therefore I do not limit myself to the precise construction shown, but feel entitled to all such variations as come within the scope of my device.

5 Having thus described my invention, what I claim as new, and desire to secure by Letters Patent, is—

1. In an axle-lubricator, a lubricant-receptacle, in combination with a plunger provided ¹⁰ with a handle extending between the spokes, in the manner and for the purpose substantially as described.

2. In an axle-lubricator, a lubricant-receptacle, in combination with a plunger provided ¹⁵ with a spring - handle, substantially as described.

3. In an axle-lubricator, a lubricant-receptacle, in combination with a plunger provided ²⁰ with a laterally - extending handle having a coil-spring, substantially as described.

4. In an axle-lubricator, a lubricant-receptacle inserted in the hub between the spokes and rim, in combination with a plunger provided with a handle extending laterally ²⁵ between the spokes and being locked in place by

a catch located upon one of the spokes, substantially as described.

5. In an axle-lubricator, a lubricant-receptacle, in combination with a plunger provided with a handle having a spring-coil located ³⁰ between the plunger and free end of the handle, substantially as described.

6. In an axle-lubricator, a lubricant-receptacle provided with a plunger having a laterally-extending handle and free end extending ³⁵ substantially at right angles to the body portion of the handle, in combination with a catch, as specified.

7. In an axle-lubricator, a lubricant-receptacle inserted in the hub of the wheel, in combination with a plunger having a handle in engagement with one of the wheel-spokes, whereby the plunger is retained in place, substantially as described.

In testimony whereof I affix my signature in ⁴⁰ presence of two witnesses.

WARREN COLE, JR.
